UNITED STATES PATENT OFFICE.

PHILIP JACOBSON AND ISIDORE S. MOSCOVITZ, OF NEW HAVEN, CONNECTICUT.

ALARM DEVICE.

Application filed January 19, 1922. Serial No. 530,334.

To all whom it may concern:

Be it known that we, PHILIP JACOBSON, a citizen of the United States, and ISIDORE S. MOSCOVITZ, a subject of Ferdinand I, King of Rumania, residing at New Haven, in the county of New Haven and State of Connecticut, have invented certain new and useful Improvements in Alarm Devices, of which the following is a specification, reference being had therein to the accompanying drawings.

Our invention relates to an alarm device, the principal object of which is to provide a mechanism of this character having duplex alarms, one a bell and the other a buzzer, or the like.

Among other aims and objects of the invention may be recited the provision of a device of the character mentioned with a view to compactness, in which the number of parts are few, construction simple, cost of production small and efficiency and operation high.

The improvements in the details and arrangement of parts will be apparent from an inspection of the accompanying drawings, in connection with the description hereinafter contained and wherein a preferred embodiment of the invention is disclosed for the purpose of imparting an understanding of the same.

In the drawings:

Figure 1 is a front elevation of our improved alarm device; and

Figure 2 is a fragmentary sectional view thereof, taken generally upon line 2—2 of Figure 1.

Having more particular reference to the drawings and in connection with which like reference characters refer to corresponding parts, 10 represents the base member, 12 and 13 two magnet coils which are connected with a plate 14 forming part of the base member 10 and 11 the bell. All of these parts are of a common type and well known in the art.

Fixed to a standard 15 connected with the base member 10 by the plate 16 and screws 17 or the like, is an armature spring 18, which is provided with companion arms 19 and 20 which terminate in spring fingers 46 and 47, the former being shown slightly longer than the latter, but may be of the same length, if desired.

To the arm 19 is fixed the bell armature 21 having the rod 22 connected therewith

with a ball 23 upon its outer end, and to the arm 20 is fixed the buzzer armature 24. Both of the armatures 21 and 24 are so arranged relatively to the coils 12 and 13 that they are directly opposite the cores 25 thereof.

Attached to the underside of the base member 10 is a plate 26 of fiber or similar non-conducting material, to which is secured the contact standards 27 and 28, the former of which terminates at its upper end with an inwardly projecting contact point 29 opposite the finger 46, and the latter in the contact point 30 opposite the finger 47.

Connected with the base member 10 are three binding posts 31, 32 and 33, these being of the usual form with binding nuts 34 thereon.

The wiring of this device comprises a connection 35 between the contact standard 27 and the binding post 32, a connection 36 between the binding post 31 and the contact standard 28 and a connection 37 between the coil 13 and the binding post 33, these latter coils being connected with each other in the usual manner, and the coil 12 with the base member 10, or ground by the wire 38.

The numeral 39 designates the battery, 40 the bell push button and 41 the buzzer push button, both of which are connected with the battery by the wire 42 and the former to the binding post 31 by the wire 43 and the latter to the binding post 31 by the wire 44, the battery and binding post 33 being connected by the wire 45.

In operation by manipulating the bell push button 40 the bell circuit is closed and the ball 23 strikes the bell 11 sounding the alarm. Likewise when the buzzer push button 41 is manipulated the buzzer circuit is closed and the buzzer is operated.

The method of the operation of the armatures 21 and 24 toward and away from the cores 25 of the coils 12 and 13 when the latter are energized, is well known and requires no detailed description herein. The new feature, however, is the association of the two armatures with the coil and means for independently operating each from different points and producing either a loud alarm as with the bell, or a light alarm as with the buzzer. Thus the device is adapted for an nunciator purposes to indicate that the alarms, whether that of the bell or buzzer, are being sounded from two different places.

The weight of the buzzer armature is

much less than that of the combined bell armature and the rod 22 and ball 23, hence when the buzzer armature is actuated through the closing of its circuit, its vibration is so relatively rapid that no movement is imparted to the bell armature which remains practically stationary.

This device might be utilized with the bell alarm for instance at the front door 10 of a residence and the buzzer alarm push button at the rear door or vice versa, the character of the sound caused by the manipulation of either push button indicating the location of the button. A bell 15 with a different tone may be substituted, if desired, for the buzzer alarm.

Minor changes and alterations may be made within our invention, aside from those herein suggested, and we would therefore 20 have it understood that we do not limit ourselves to the exact construction herein shown and described, but claim all that falls fairly within the spirit and scope of the appended claims.

25 What we claim as new and desire to secure by Letters Patent, is:

1. In an alarm device of the character described; a magnet; an armature spring having companion arms connected therewith; a bell armature connected with one of said arms; a buzzer armature connected with the other of said arms; and a contact point for each of said armatures.

2. In an alarm device of the character 35 described; a magnet; an armature spring having companion arms connected therewith; a bell armature connected with one of said arms; a buzzer armature connected with the other of said arms, and greater in length 40 than the bell armature; and a contact point for each of said armatures.

3. In an alarm device of the character described; a magnet; an armature spring having companion arms connected there- 45

with; a bell armature connected with one of said arms; a buzzer armature connected with the other of said arms; one of said armatures being longer than the other; and a contact point for each of said armatures.

4. In an alarm device of the character 50 described; a magnet; an armature spring having companion arms connected therewith, and secured to a fixed part; a bell armature connected with one of said arms; a buzzer armature connected with the other 55 of said arms, and a contact point for each of said armatures.

5. In an alarm device of the character 60 described; a magnet; an armature spring having companion arms connected therewith; a bell armature connected with one of said arms; a buzzer armature connected with the other of said arms, the combined width of the armatures being no greater than that 65 of the core of said magnet, and a contact point for each of said armatures.

6. In an alarm device of the character 70 described; a magnet; an armature spring having companion arms connected therewith; a bell armature connected with one of said arms; a buzzer armature connected with the other of said arms, with an open space between it and the bell armature, and a contact point for each of said armatures.

7. In an alarm device of the character 75 described; a magnet; an armature spring having companion arms connected therewith; a bell armature connected with one of said arms; a buzzer armature connected with the other of said arms; and a contact point 80 for each of said armatures, each of the companion arms of said armature spring near the outer end being out of contact with the armature connected therewith.

In testimony whereof we have hereunto 85 affixed our signatures.

PHILIP JACOBSON.
ISIDORE S. MOSCOVITZ.
